VEHICLE DOOR MIRROR MOUNTING BRACKET

Joseph R. Bourassa, Huntington, and Manuel Lopez,
Trumbull, Conn., assignors to Parker-Hannifin Corporation,
Shelton, Conn.

Filed Sept. 13, 1974, Ser. No. 505,737

Term of patent 14 years

Int. Cl. D12—16

U.S. Cl. D12—187

FIG.1

FIG.2

6

FIG. 3

FIG. 4

FIG. 5

FIG. 6

FIG. 1 is a perspective view of a vehicle door mirror mounting bracket embodying our new design;

FIG. 2 is a side elevational view thereof;

FIG. 3 is a top plan view thereof;

FIG. 4 is a front elevational view thereof;

FIG. 5 is a rear elevational view thereof; and

FIG. 6 is a fragmentary sectional view thereof taken along line 6—6 of FIG. 2.

The broken lines seen in FIGS. 1—5 represent variable environmental elements which form no part of the present design.

We claim:

The ornamental design for a vehicle door mirror mounting bracket, substantially as shown and described.
